UNITED STATES PATENT OFFICE.

ALVIN W. PUFFER, OF MEDFORD, MASSACHUSETTS, ASSIGNOR TO THE PUFFER MANUFACTURING COMPANY, A CORPORATION OF MAINE.

BOTTLE-COOLER.

SPECIFICATION forming part of Letters Patent No. 690,076, dated December 31, 1901.

Application filed July 19, 1901. Serial No. 68,872. (No model.)

To all whom it may concern:

Be it known that I, ALVIN W. PUFFER, of Medford, county of Middlesex, and State of Massachusetts, have invented an Improvement in Bottle-Coolers, of which the following description, in connection with the accompanying drawings, is a specification, like letters on the drawings representing like parts.

10 The present invention relates to a bottle-cooler adapted to be used in conjunction with soda-water-dispensing apparatus, the invention relating to that class of apparatus in which the syrups are contained in bottles, which are kept in a stand or holder and exposed to a suitable cooling medium.

15 The object of the invention is to obtain a bottle-cooler in which the several bottles may be inclosed in a cooled space, containing, for example, an ice-tank, and each bottle rendered accessible without leaving the cooled space open to the action of the external heat, so that the ice is preserved while the bottle is in use, the bottles when not in use being 25 inclosed in the cooled space and protected from the heat of the outer air.

20 In accordance with the invention the stand or holder which contains the bottles is arranged to inclose the cooling medium and is 30 provided with an individual pocket for each bottle, each of said pockets being provided with an inclosing wall or casing adapted when the pocket is in its normal position to inclose the bottle and when the pocket is in abnormal position to shut off the opening from the cooling-chamber. As herein shown, each bottle - holder comprises a cylindrical shell mounted for rotation in the stand or holder, which has wall - sections between adjacent 35 shells, and the wall of each of the said shells extends far enough around to cover or close the space between adjacent wall-sections, but not far enough to prevent the insertion or removal of the bottle. As shown, each shell is 40 substantially the size of the bottle and the wall extends about half around to expose the bottle, so that when the bottle pocket or shell is turned half around to expose the bottle the wall of the shell closes the space behind the 45 bottle, and when the bottle-pocket is turned back to normal position the wall closes the

space in front of the bottle, the bottle, however, being exposed to the cooling medium.

A further feature of the invention consists in the combination, with the bottle-pockets 55 arranged as described, of an annular rotatable stand or holder surrounding the cooling medium, so that by turning the stand any bottle-pocket desired can be brought to a convenient position for the removal and use of 60 the bottle.

Figure 1 is a view, partly in section and partly in elevation, of an apparatus embodying the invention; and Fig. 2 is a horizontal section of the same. 65

70 In accordance with the invention the bottle-pockets *a*, which contain the syrup-bottles *A*, are mounted in the frame *b*, shown as having upper and lower members suitably connected together and arranged to rotate, the lower member being shown as mounted on balls or other antifriction devices *b*², traveling in a ball-race *c*², formed in a support *c*, which is shown as projecting laterally from an internal chamber *c*³, arranged to be filled 75 with ice or other cooling mixture, which is suitably confined by a wall *c*⁴, herein shown as having openings or perforations. The lower member of the support *b* is shown as provided with a flange or skirt portion *b*³, which overhangs and incloses the support *c*, and the said support *c* is provided at its upper end with an overhanging cover *c*⁵, which projects beyond the pockets *a* and covers the tops thereof, the said cover *c*⁵ being shown as connected with 80 the internal cooling-chamber *c*³. The upper and lower members of the rotatable support *b* are shown as connected together by wall-sections *b*⁴, each of which extends from one of the pockets *a* to the next, so that in conjunction with the said pockets the said wall members *b*⁴ afford a substantially closed case surrounding the cooling-chamber *c*³. 85

90 Each of the pockets *a* consists of a base *a*² and top *a*³, circular in shape, and a wall, 95 which is shown as substantially semicylindrical, thus affording a space for the removal of the bottle from the pocket, which bottle fits the base portion and is held in place by the flange *a*⁴, which extends wholly around the 100 base portion *a*². The said bottle-pockets are so arranged with relation to the wall-sections

*b*⁴ that one end of the wall of each pocket lies in contact with one of the wall-sections *b*⁴ when the pockets are closed, the next wall-section *b*⁴ lying against the side of the wall-section of the pocket *a*, so that one of the said wall-sections constitutes a stop for the pocket when turned upon its pivotal bearing in the member *b*, one edge of the cylindrical wall coming in contact with the side of the wall-section when the bottle is exposed and the other edge coming in contact with the other side when the bottle is closed in.

Referring to the lower portion of Fig. 2, the left-hand pocket *a* is shown as closed and the right-hand pocket is shown as open, each pocket being provided with a handle or finger piece *a*⁵ for rotating the pocket around its axis. By moving the finger-piece *a*⁵ to the right, as indicated in Fig. 2, it will be seen that the wall of the pocket will be moved around until it closes the space between the adjacent wall-sections *b*⁴, leaving the open portion of said pocket exposed for the removal of the bottle, the cooling-chamber *c*³, however, being protected from the external air, as indicated in said Fig. 2, where the right-hand lower pocket is shown as open.

The wall-section *b*⁴ is arranged to extend into the opening in the wall of the pocket *a*, so as to constitute a stop therefor in either position, as above stated, and the closed portion of the pocket is of such extent as to close the opening in either position of the pocket, whether the bottle is exposed or within the chamber. Each of the pockets may be provided on its outer wall with a label, indicating the kind of syrup inclosed, and the carrier *b* for the pockets may be rotated easily until the pocket desired is in a convenient position, after which the pocket may be rotated by means of the handle *a*⁵, thus exposing the bottle, but at the same time inclosing the cooling-chamber, so as to prevent waste of ice by contact with the external air.

The bearings for the pockets are shown as projections *a*⁶ from the outer surfaces of the lower members *a*², the said projections entering openings in the lower annular member of the support *b*, while the pockets bear at the top on pins or projections *a*⁷, which may be inserted through the upper annular member of the support *b*, thus facilitating the assembling of the parts.

In order to keep the pockets open or closed, the support *b* is shown as provided with yielding projections *b*⁶, which may be formed by bending up portions of a spring *b*⁷, supported on the lower member of the said support *b*, these projections yieldingly pressing against the bottoms *a*² of the several pockets, which in turn are provided with recesses *a*⁸, properly positioned to receive the projections *b*⁶ when the pockets are wholly open or wholly closed.

The pressure of the yielding projections is sufficient to prevent the pockets from opening accidentally, but is easily overcome by

pressure on the handles *a*⁵, so that the pockets can be readily manipulated when desired.

It is to be understood that the invention is not limited to the specific construction and arrangement shown and described, since modifications may be made without departing from the invention. It is obviously immaterial, for example, how the cooling-chamber is arranged or shaped so far as relates to the combination therewith of the pockets, said pockets being easily adaptable for use in connection with any chamber which should be kept always closed to prevent waste.

I claim—

1. In a dispensing apparatus, the combination with a rotatable frame having a wall provided with openings therein; of a stationary receptacle for a cooling medium inclosed within the said wall, there being an annular space between the chamber and the wall; a rotatable pocket or support for a bottle in each opening in the said wall; and an inclosing shell for each pocket extending from one side of the said opening to the other to close said annular space, as set forth.

2. In a dispensing apparatus, the combination with a stationary support for a cooling medium; of a rotatable annular frame extending and rotating around the said support, said frame having wall-sections to inclose the said support; and bottle-pockets rotatably mounted in said frame, each pocket having a cylindrical wall extending partially around it, to close the space between adjacent wall-sections, as set forth.

3. The combination with a cooling-chamber provided with an annular cover above and an annular support below; of a rotatable frame surrounding said chamber, said frame comprising annular upper and lower members connected together by wall-sections, the lower member having a bearing on said annular support; and pockets for bottles rotatably mounted between said members, each pocket having a cylindrical wall extending partially around it from one wall-section to the next, as set forth.

4. The combination with the cooling-chamber provided with an annular support; of a rotatable frame surrounding said chamber and having a bearing on the said support; pockets for bottles rotatably mounted in said frame, each pocket having a cylindrical wall extending partially around it; wall-sections between adjacent pockets, the cylindrical walls of the pockets and said wall-sections completely inclosing the cooling-chamber; and yielding retaining devices for said rotatable pockets, as set forth.

In testimony whereof I have signed my name to this specification in the presence of two subscribing witnesses.
